BALL-BEARING SPINDLE

Application filed January 12, 1928, Serial No. 246,324, and in Canada April 25, 1927.

In efforts at using ball-bearings for the bowl-spindle of centrifugal liquid separators the difficulty in protecting the ball-bearings, especially at the neck-bearing, supporting the spindle at its top end, against the entering of milk, water and the like is met. The means generally used for effecting a tight joint between a rotating shaft and the stationary member of its bearing and consisting of felt or the like would not be effective. Owing to the great speed of the spindle the felt would be worn out very rapidly. Another method of protecting the ball-bearing against foreign matters and consisting in filling the bearing with grease cannot be used owing to the great speed of the spindle, which permits only the use of light oil for the lubricating of the ball-bearing here in question.

Owing to the fact, however, that an indispensable condition for profiting by the advantages of ball-bearings or, on the whole, for applying the same at all, consists in that the bearing is protected against the entering into the same of foreign matters and especially moisture, which would cause the balls to rust, a fully satisfactory solution of the problem of using ball-bearings for the separator members in question is not possible, without the said condition being fulfilled. This is effected by rendering the bowl-spindle sleeve-shaped and mounting the ball-bearings inside the same. This arrangement is applicable especially to centrifugal liquid separators, in which the driving device comprises a worm-wheel meshing with screw threads on the bowl-spindle.

The present invention relates to arrangements of the spindle, the ball-bearings and members appertaining to the same through which many advantages are gained, which will be stated after the construction of the spindle has been described.

In the accompanying drawing Fig. 1 shows in a vertical section a form of execution of the invention; the said figure shows the spindle mounted in a cream separator, the frame of which is shown in vertical section, while the bowl is shown in a side view, partially in section. Fig. 2 shows in a ver-

tical section a spindle arranged in accordance with a second form of the invention.

In the form of the invention shown in Fig. 1, the bowl spindle consists of a stationary carrier spindle 1, fixed in the frame 2 of the separator, and a running spindle comprising an outer sleeve 3 and an inner sleeve 4 slid into the sleeve 3 and fitting closely to the same. The outer sleeve 3 is extended downwards and provided with screw-threads 5 engaged by the ordinary worm-wheel 6, which in the shown separator rotates in an oil-bath contained in a pit provided in the frame 2 of the separator. Motive power is transmitted to the said worm-wheel 6 in any suitable manner. The inner sleeve 4 is extended upwards and constitutes a journal 7 carrying the separator bowl 8. The running spindle 3, 4 is journalled in two ball-bearings, which are mounted on the central carrier spindle 1. The dimensions of the carrier spindle 1 may be so adapted, that the vibrations of the bowl 8 and the running spindle are absorbed by the carrier spindle itself, or the carrier spindle and the mounting of same may be so arranged, that the said vibrations are absorbed partly by the springy spindle 1 and partly by a springy connection of the spindle 1 with the frame of the separator, effected preferably by a special, suitably adapted play between the spindle 1 and the sleeve shaped part 9 of the frame, in which the spindle is mounted, said part being filled with oil. The inner ball race 10 of the lower ball-bearing is forced on the spindle 1 and supported by a flange 11 provided on the same. The outer ball-race 12 of the said ball-bearing is located between an offset 13, provided in the outer sleeve 3, and the lower end of the inner sleeve 4. The inner ball race 14 of the upper ball-bearing is supported by an offset 15 provided on the top end of the carrier spindle 1, while the outer ball-race 16 of the said bearing bears against the inner side of the inner sleeve 4. A screw-threaded ring 17 meshes with screw-threads provided on the top end of the outer sleeve 3 and engages the inner sleeve 4 by means of an inner flange 18, thus locking the inner sleeve 4 in the outer sleeve 3. A pin 19 fixed in the sleeve 4 and

extending through an axial slot in the sleeve 3 connects the sleeves, so that the driving power is transmitted from the sleeve 3 to the sleeve 4 and the bowl 8 connected to the sleeve 4 by a cross pin 20.

In the bottom wall of the sleeve 3 a circular groove 21 is provided, which serves as a magazine, in which lubricating oil from the ball-bearings is gathered, as the separator is brought to a standstill. As the separator and the running spindle 3, 4 are again rotated, oil contained in the groove 21 is caused by the centrifugal force to enter the lower ball-bearing 10, 12 by which it is then minutely divided and spread as a fine dust inside the sleeve 4, the upper ball-bearing 14, 16 being thus also lubricated.

In the form of the spindle shown in Fig. 2, which is adapted to greater cream separators, 20 a sleeve 22 is slid into a sleeve 23 in the same manner as in Fig. 1, and the lower extended end of the outer sleeve constitutes a screw 24 adapted to be engaged by a driving worm-wheel, while the extended upper end 25 of the 25 inner sleeve 22 constitutes a journal for the separator-bowl in the same manner as in Fig. 1. Also in this form of execution two ball-bearings are provided between the running spindle 22, 23 and the carrier spindle 26. The 30 carrier-spindle 26 is adapted to be fixed in the frame of the separator in the same manner as the spindle 1, Fig. 1. The inner ball-race 27 of the lower bearing is held between an offset 28 on the carrier spindle 26 and a 35 sleeve 29 in screw-threaded engagement with the spindle 26. Sleeve 29 extends upwards along the spindle 26 to the vicinity of the upper ball bearing for the purpose stated below. The inner ball-race 30 of the upper ball-bearing is held between an offset 31 on the spindle 26 and a nut 32 screwed on the top of the carrier spindle 26. Between the lower end of the inner sleeve 22 and the outer ball-race 33 of the lower ball-bearing a spiral 40 spring 34 is located, and between the outer ball-race 35 of the upper ball-bearing and the inner sleeve 22 a second spiral spring 36 is 45 provided. A screw-threaded ring 37 meshing with the outer sleeve 23 and engaging the inner sleeve 22 by means of an inner flange 38 prevents the inner sleeve acted upon by the springs 34 and 36 from leaving the outer sleeve. In the bottom of the sleeve 23 a circular groove 39 for lubricating oil is provided and the lubrication of the ball-bearings is effected in the same manner as in the construction illustrated in Fig. 1. A screw 40 is fixed in the sleeve 22 and the head of the said screw is in engagement with an axial slot 41, provided in the sleeve 23, and transmits the motion of the sleeve last mentioned to the sleeve 22 and the bowl in the same manner as the pin 19, Fig. 1.

As perceived from the drawing the bowl-spindle, comprising the stationary carrier

spindle and the running spindle constitutes a practically hermetically closed chamber, in which the ball-bearings are protected against waste milk and water and against oil contained in the pit and spread in the same by the rotating worm-wheel 6. The said oil when used for a longer period, will be mixed with small particles worn from the worm-wheel, and often also with milk and water, which has entered the said pit from the cup shaped part of the separator frame enclosing the bowl 8, which oil for that reason would be very injurious to the ball-bearings. Also the lubricating oil provided in the said closed chamber is protected against dirt and prevented from leaving the chamber. For that reason the consumption of oil for lubricating the ball-bearings is reduced to a minimum, and experiments have proved that a separator provided with a bowl-spindle arranged in accordance with the present invention may be run for years without any fresh oil being supplied. The bowl-spindle, comprising as stated the carrier spindle and the running spindle, constitutes a unit which may be removed in a convenient manner when worn for instance, and for which a new one may easily be substituted.

The ball-bearings shown in the drawing are of the modern type having a single series of balls and great bearing surfaces for the same but not special opening for the introducing of the balls into the space between the ball races. The said ball-bearings are specially apt to sustain axial as well as radial strain at the great number of revolutions (6000-9000 per minute), at which cream separators generally are rotated. In the spindle shown in Fig. 1 the lower ball-bearing is adapted to sustain the whole weight of the separator bowl, while the upper ball-bearing only serves to sustain the running spindle radially. In the form of execution shown in Fig. 2 the weight of the bowl is distributed on both ball-bearings, the axial pressure being transmitted to the outer ball races 33 and 35 by the springs 34 and 36, so that the bowl is supported in a yieldable manner, the yielding movement being limited downwards by the sleeve 29. About $\frac{2}{3}$ of the whole load is sustained by the lower ball-bearing and $\frac{1}{3}$ of the load by the upper bearing in accordance with the strength of the springs. Through the distribution of the load on both ball-bearings, bearings of a smaller size may be used, the outer diameter of the running spindle being thereby correspondingly reduced. The ball-bearings shown in the drawings are to be preferred to such axially acting ball-bearings as consist of balls located between two parallel discs, perpendicular to the spindle. Ball-bearings of this construction are able to sustain very great axial loads but have proved

unfit at the great velocity, at which separators are run, owing to the fact that the centrifugal force acting upon the balls is so great, that the balls tend to force the said discs from one another and overstrain the ball-cage.

The invention may evidently be modified in some respects without exceeding the limits of the same.

I claim:

- 10 1. In a ball-bearing spindle for centrifugal separator bowls the combination of a central stationary carrier spindle and a running spindle enclosing the same and comprising two sleeves one slid into the other and connected to the same, one of the said sleeves being arranged to transmit motion to the running spindle and the other sleeve arranged to carry the bowl.
- 20 2. In a ball-bearing spindle for centrifugal separator bowls the combination of a central stationary carrier spindle, a running spindle enclosing the same and comprising two connected sleeves one slid into the other, means provided on one of the sleeves for transmitting motion to the running spindle, an axial extension of the other sleeve arranged to carry the bowl, and radially and axially acting ball bearings located between the carrier spindle and the running spindle and sustaining the latter.
- 30 3. In a ball-bearing spindle for centrifugal separator bowls the combination of a stationary carrier spindle, a running spindle, comprising an inner sleeve and an outer sleeve slidably connected, means provided on one of the sleeves for transmitting motion to the running spindle, an axial extension of the other sleeve, arranged to carry the bowl, radially and axially acting ball bearings located between the carrier spindle and the running spindle and sustaining the latter, and yielding means supporting the bowl carrying sleeve.
- 40 4. In a ball-bearing spindle for centrifugal separator bowls the combination of a stationary carrier spindle, a running spindle, comprising two sleeves one slid into the other and connected to the same, means provided on one of the sleeves for transmitting driving power to the running spindle, an axial extension of the other sleeve, arranged to carry the bowl, radially and axially acting ball bearings located between the carrier spindle and the running spindle and sustaining the latter, springs provided between the bowl carrying sleeve and the ball-bearings and an abutment limiting the yielding downward movement of the sleeve last mentioned.
- 50 5. In a ball-bearing spindle for centrifugal separator bowls the combination of a central stationary carrier spindle and a running spindle enclosing the same and comprising two connected sleeves one slid into the other, one of the said sleeves being arranged to transmit

motion to the running sleeve and the other sleeve arranged to support the bowl, and a groove provided in the bottom of the running sleeve and serving as a magazine for lubricating oil for the ball-bearings while the separator is at a standstill.

In testimony whereof I have hereunto affixed my signature.

JOHANNES VALDEMAR MÄRTEN RISBERG.
